CLAIM

The ornamental design for a multifunction food processor part, as shown and described.

DESCRIPTION

FIG. 1 is a perspective view of a multifunction food processor part, showing the first embodiment of my new design; FIG. 2 is a front plan view thereof; FIG. 3 is a rear plan view thereof; FIG. 4 is a left side plan view thereof; FIG. 5 is a right side plan view thereof; FIG. 6 is a top plan view thereof; and FIG. 7 is a bottom plan view thereof.

FIG. 8 is a perspective view of a second embodiment of an ornamental design for a multifunction food processor part; FIG. 9 is a front plan view thereof; FIG. 10 is a rear plan view thereof; FIG. 11 is a left side plan view thereof; FIG. 12 is a right side plan view thereof; FIG. 13 is a top plan view thereof; and, FIG. 14 is a bottom plan view thereof.

The broken lines showing portions of the article form no part of the claimed design.
